UNITED STATES PATENT OFFICE

VICTORIA CALCAGNI, OF WORCESTER, MASSACHUSETTS, ASSIGNOR TO GABRIELE MAU-
RIELLO, OF WORCESTER, MASSACHUSETTS

DESIGN FOR AN ICE-CREAM CONE

Application filed July 1, 1930. Serial No. 36,249. Term of patent 3½ years.

To all whom it may concern:

Be it known that I, VICTORIA CALCAGNI, a subject of the King of Italy, residing at Worcester, in the county of Worcester and State of Massachusetts have invented a new, original, and ornamental Design for Ice-Cream Cone of which the following is a specification, reference being had to the accompanying drawing forming part thereof.

Fig. 1 is a front view, and
Fig. 2 is a side view showing my new design.

I claim:

The ornamental design for an ice-cream cone as shown.

VICTORIA CALCAGNI.
